UNITED STATES PATENT OFFICE.

JAMES H. STODDARD, OF LOS GATOS, CALIFORNIA.

COMBINATION-TOOL.

986,239.

Specification of Letters Patent.

Patented Mar. 7, 1911.

Application filed September 2, 1909. Serial No. 515,750.

To all whom it may concern:

Be it known that I, JAMES H. STODDARD, a citizen of the United States, residing at Los Gatos, in the county of Santa Clara and 5 State of California, have invented certain new and useful Improvements in Combination-Tools, of which the following is a specification.

My invention relates to an improvement 10 in combination tools, and the object is to provide more particularly a combined square, bevel, and compass tool. The blades are so connected to each other that it may be used as a try-square, miter cutter, and compass. 15 It is also capable of such adjustments for indicating the bevels and miters that may be removed and cut as polygon miters from three-sided to ten-sided figures.

The invention consists of certain novel features of construction and combinations of parts which will be hereinafter fully described and pointed out in the claims.

In the accompanying drawings—Figures 1 and 2 are views taken from opposite sides, 25 showing the parts differently adjusted. Fig. 3 is a view showing all of the members assembled in a small compass, and Fig. 4 is a detailed sectional view showing the manner of connecting one of the blades to the quadrant portion of the other blade.

A, represents one of the blades which is provided with a quadrant head 1 at one end having a degree scale of a half circle thereon, and B is the other blade, which is 35 pivotally connected to the blade A at the quadrant head 1 by a screw threaded stud 2 passing through the head 1. A thumb nut 3 and screw-threaded stud 2 connect blade A to the head 1. Holes 5 are formed in the 40 quadrant head at the degree points of the half circle, and an opening 6 is formed in one end of the blade B, which is adapted to register with the openings 5 in the quadrant head. A latch 8 is mounted on the stud 2 45 and is held upon the quadrant head by the thumb nut 3. The latch is provided with a lug 9 which is adapted to pass through the openings 5 in the quadrant head through the opening 6 in the blade B for forming a 50 square or miter cut. A knob 10 is formed on the latch whereby the lug can be removed from the openings for releasing the blade B. The ends of the blades A and B are beveled at an angle of 45° and tapered to sharp 55 points 11 and 12, respectively. By loosening the thumb nut 3 the latch can be re-

moved out of engagement with the openings 5 and the blades A and B are capable of free movement whereby they can be used as a compass.

On the under side of the quadrant head a scale is formed for cutting polygon miters from three-sided to 10-sided figures. The blade B is notched as at 15, and by bringing the notched edge to any point on the scale that miter can be measured and cut. The thumb screw 3 is tightened to hold the blade at that point upon the scale so that the exact measurement can be obtained. In order to get the angle for a five-sided polygonal miter, the edge of the notch 15 is brought to one of the points 5 on the scale.

An angle blade C is provided with an elongated slot 16 through which extends a stud 17 on the blade A. A thumb nut 18 is received upon the stud for holding the angle blade in its different adjustments for obtaining any bevel and is used when the miter square is formed. The angle blade is graduated along both edges and the blade B is 80 graduated on both sides. The angle blade is adapted to be swung in either direction at an angle of 45°. Stops or flanges 20 and 21 are formed on the blade A for retaining the blades B and C in proper position when the parts are folded into small compass. The stops also limit the movement of the blade B. The latch 8 is adapted to engage the blade B by the lug passing through the opening in the zero point and holding the 90 blade in proper position when the parts are brought together or formed into a small compass.

It is evident that more or less slight changes might be resorted to in the form and arrangement of the several parts described without departing from the spirit and scope of the invention, and hence I do not wish to be limited to the exact construction herein set forth, but:

Having fully described my invention, what I claim as new and desire to secure by Letters Patent is:

1. A combination tool comprising a blade having a quadrant head thereon and provided with a scale of graduations thereon, a secondary blade pivoted to the quadrant head, said blade and quadrant head having registerable holes therein, and a stud pivotally connecting the blades together, of a latch having a lug adapted to enter said holes when registered, whereby to lock the,

blades in an adjusted position, one end of said latch held on the stud, and a nut adapted to screw on the stud whereby to hold the latch and the blades together at a common pivotal point.

2. A combination tool comprising a blade having a quadrant head thereon and provided with a scale of graduations thereon, a secondary blade pivoted to the quadrant head; said blade and quadrant head having registerable holes therein, and a stud pivotally connecting the blades together, of a latch having a lug adapted to enter said holes when registered, whereby to lock the blades in an adjusted position, one end of said latch held on the stud, and a nut adapted to screw on the stud whereby to hold the latch and the blades together at a common pivotal point, an angle blade having an elongated slot therein, a stud on one of the first-mentioned blades passing through said elongated slot, and a thumb-nut on the stud, said first-named blades having stops on their edges for retaining the blades in proper position when the parts are folded into small compass.

3. A combination tool comprising a blade having a quadrant head thereon and provided with a scale of graduations thereon, a secondary blade pivoted to the quadrant head, said blade and quadrant head having registerable holes therein, and a stud pivotally connecting the blades together, of a latch having a lug adapted to enter said holes when registered, whereby to lock the blades in an adjusted position, one end of said latch held on the stud, and a nut adapt-

ed to screw on the stud whereby to hold the latch and the blades together at a common pivotal point, an angle blade having an elongated slot therein, a stud on one of the first-mentioned blades passing through said elongated slot, and a thumb-nut on the stud, said first-named blades having stops on their edges for retaining the blades in proper position when the parts are folded into small compass.

4. A combination tool, comprising a blade having a quadrant head, a degree scale formed on the quadrant head, said quadrant head provided with openings, a secondary blade pivotally connected to the quadrant head having an opening therein which is adapted to register with the openings in the quadrant head, and a latch on the quadrant head adapted to pass through the opening in the quadrant head and the opening in the secondary blade for locking the blade to the head for forming the desired angle, an angle blade mounted on the first-named blade, and means for adjustably supporting the angle blade upon the first-named blade.

In testimony whereof I affix my signature, in the presence of two witnesses.

JAMES H. STODDARD.
